SHIPPING CASE FOR FRAGILE ARTICLES

Jesse R. Grant, Chicago, Ill.

Application January 16, 1948, Serial No. 2,585

4 Claims. (Cl. 229—23)

1

This invention relates to shipping cases for fragile articles composed of double-face corrugated fiber board, and has for its principal object the provision of a new and improved case of this type.

It is a main object of this invention to provide a corrugated fiber board shipping case for fragile articles, which is of standard length and width, and which contains two compartments that are of standard dimension throughout and bounded by walls which are smooth and planar and of uniform thickness from top to bottom of the case.

Another object of the invention is to provide a corrugated fiber board shipping case having a double thickness of material in the bottom and sides to strengthen the case against endwise stresses.

Another object of the invention is to provide a corrugated fiber board shipping case in which the ends and partition are composed of two thicknesses of material that are spaced apart to cushion the case against shocks imposed endwise upon it.

Another object of the invention is to provide in a corrugated fiber board shipping case, fiber board posts located at the corners of the case and at both ends of the partition therein to strengthen the case vertically and thereby increase its stacking strength.

Another object of the invention is to provide for a corrugated fiber board shipping case a cover which does not extend beyond the outer walls of the case either at the ends or sides, and which is locked to the case at both ends and in the middle.

Another object of the invention is to provide a corrugated fiber board shipping case which can be manufactured at low cost without sacrificing quality.

Further objects of the invention not specifically mentioned here will be apparent from the detailed description and claims which follow, reference being had to the accompanying drawings in which a preferred embodiment of the invention is shown by way of example and in which:

Fig. 1 is a view in isometric projection showing the case partially assembled;

Fig. 2 is a view in isometric projection of the cover for the case;

Fig. 3 is a plan view of the blank from which the bottom and sides of the case are formed;

Fig. 4 is a plan view of the blank from which one form of liner for the case is formed;

Fig. 5 is a plan view of the blank from which the cover of the case is formed;

Fig. 6 is a plan view of the blank from which the partition and end members of the case are formed;

2

Fig. 7 is a plan view of a modified blank for forming the liner for the case; and

Fig. 8 is a fragmentary cross sectional view taken along the longitudinal median line of the case, showing particularly the attachment of the bottom and end wall thereof.

Shipping cases for fragile articles such as eggs have long been made of wood, and these cases have been standardized as to width, length and height, so as to properly fit in railway cars, trucks and cold storage rooms with a minimum of waste space. It is essential that such cases be maintained accurately to these dimensions so as to snugly fit into the car or truck to minimize damage to the contents resulting from shocks encountered in shipping.

Double-face corrugated fiber board egg cases have recently come into quite general use, notwithstanding that most of these cases are not of standard dimensions. In my prior co-pending applications, Serial No. 649,211, filed February 21, 1946, now Patent No. 2,578,060, dated December 11, 1951, and Serial No. 678,462, filed June 21, 1946, now Patent No. 2,573,706, dated November 6, 1951, there are shown such cases which maintain standard dimension both as to length, width and height, and also provide compartments which are of uniform dimension from top to bottom, and bounded by smooth parallel walls that are entirely free from projections of every kind which occupy compartment space.

The present invention, which may broadly be stated to be an improvement upon these prior co-pending applications, preserves the salient features thereof, and in addition provides a shipping case particularly adapted for eggs, which will meet the requirements of both the transportation companies and packers.

Recently the American Association of Railroads, in setting up standards for shipping cases for eggs, specified that double-face corrugated fiber board cases must be provided with double thickness bottoms and double thickness side walls, and if the shipper is to obtain the benefit of the preferred rate allowed for shipment in standard cases these requirements must be met. In addition, in order to permit commercial handling of the eggs by the shipper, the case must contain standard dimension compartments bounded throughout by smooth parallel walls free from obstructions of any kind which interfere with the placing and removal of standard fillers and flats therein. The case of the present invention meets these requirements.

In its preferred form, the case of the present invention consists of an outer main member that forms the bottom and side walls of the case, which member is flanged at each end by extensions which project at right angles to the face of the section from which they project. A pair of

lining members, each forming bottom and side walls of the case, are disposed within this outer member and are similarly flanged. Two such liners, placed end to end, cooperate with the flanges on the outer member to form double thickness, inwardly projecting flanges at both ends and in the middle of the case. Generally U-shaped end members are disposed against the opposite faces of the flanges and extend across the top thereof and are secured thereto to close the ends of the case. A similar U-shaped member engages the flanges at the middle of the case to form a partition dividing the case into two equal compartments.

The case thus formed has double thickness bottom and side walls, and double thickness end walls and partition, the end walls and partition wall members being spaced apart a distance equal to two thicknesses of the material, with the result that these members are cushioned against endwise shock. The double thickness side walls, together with the double thickness bottom, resist endwise stresses placed upon the case; and since the case is fastened together at the partition, such stresses cannot bow the side walls out and damage to the contents of the case is thereby minimized. The flanges at the ends and in the middle of the case form vertical and horizontally extending posts, the vertical posts of which reinforce the case vertically thereby to increase its stacking strength.

The end walls and partition are each slotted in their upper edges and a cover for the case is provided with depending flangelike tongues adapted to enter these slots to lock the cover to the case at both ends and in the middle. The cover may be flanged along its sides and the flanges tucked down inside the side walls of the case thereby to more tightly bind the top layer in the case to minimize damage to the contents thereof. The cover thus constructed fits entirely within the outer surfaces of the case and aids in reinforcing it against stresses placed upon it from any direction.

When composed of double-face corrugated fiber board of a thickness that is readily available, the case so constructed will be of standard length, width and height, and each compartment will be full size in every direction. There will be no cleats or other protuberances extending into the compartments to occupy the space thereof.

Referring now to the drawings in more detail, particularly Figs. 1 and 3, it will be seen that the outer main body of the case consists of a bottom 1 and sides 2 and 3 integral with the bottom and adapted to be folded at right angles thereto along score lines 4. End projections 5 and 6 of the bottom section 1 are integral therewith and adapted to be folded at right angles therewith along score lines 7. End projections of the sides 2 and 3 are likewise integral therewith and adapted to be folded at right angles thereto along score lines 8. It will be noted that these end projections of the side walls are cut away at 9, so that when the side walls and end projections are folded at right angles to each other and to the bottoms, the side projections will overlie the bottom projections 5 and 6 and be disposed in the same plane as those projections.

Liners, such as are shown in Figs. 4 and 7, consist of a bottom section 11 and side wall sections 12 and 13, the bottom section 11 having one end projection 14 connecting thereto along score line 15 and adapted to be folded at right angles thereto. The side wall sections 12 and 13 have simi-

lar projections 16 adapted to be folded along score line 17, which projections 16 have cutouts 18 so that when folded the projections 16 will lie in the same plane and upon the bottom projection 14.

The opposite ends of the liners have similar projections 19 and 20, the adjacent ends of which are mitered so that when these projections are folded along score line 21 all will lie in a common plane. As will be seen in Fig. 1, two such liners 10 and 10a are employed in the case and are registered with the outer main member 1.

The ends of the case are formed blank, as shown in Fig. 6, and consist of vertical wall members 25 and 26 joined together by a shorter top member 27, the members 25 and 26 being bent along score lines 28 at right angles to the top member. The U-shaped structure thus formed is fitted down over the flanges consisting of the flanges formed by the projections on the main and liner members with the faces 25 and 26 thereof registering with the opposite faces of the flanges. The end wall thus formed is secured to these flanges in any preferred manner, such as by staples 30, to close the end of the case. The two ends of the case are thus formed and a similar partition member 36 is registered with and secured to the central flange formed by the projecting ends of the liner members in any preferred manner such as by staples 37.

Thus it will be seen that the case so formed consists of a double thickness bottom, double thickness side walls, and double thickness end walls and partition both of which have face members spaced apart a distance equal to two thicknesses of the material.

It will be noted that the end wall and partition members each contains a centrally located slot 40 adapted to receive the tongues of the cover. As will be seen in Fig. 5, the cover comprises main sections 44 and 45 having tongues 46 projecting at right angles to the main plane thereof. The tongues 46 comprise two thicknesses of material and are shaped with locking members 47 by which the cover is secured to the case through engagement of these members with the under sides of the top portions 27 of the end walls and partition to securely lock the cover to the case at both ends and in the middle. Cover sections 44 and 45 may also be provided with side flanges 48 which fit down inside the side walls of the case when the cover is in place thereon. If desired, the side walls of the case may be provided with ventilating holes 50 and the end walls of the case with similar holes 51 to provide for ventilation as required in storage. In cases to be used solely for shipment, these ventilating ports ordinarily are not necessary. The end walls of the case are also provided with hand holes 52 to facilitate handling of the case.

In the embodiment shown in Fig. 7, the liner members shown in Fig. 4 are modified by forming mitered cutouts 60 at both ends of the liner so that the posts formed at the corners of the case will be mitered rather than step-cut, as shown in Fig. 4.

From the foregoing it will be seen that the case of the present invention has end walls having thickness equal to four thicknesses of material and having two parallel members that are spaced apart a distance equal to two thicknesses of the material. This construction builds into the end wall of the case a certain amount of resiliency so as to cushion shocks imposed upon the case in transit. It is well known that switching, starting and stopping of freight trains frequently im-

pose severe endwise shock on the contents of the cars, and this resiliency cushions the load within the case and minimizes damage resulting from such shock. The partition is similarly constructed and cushioned.

Since the side walls and bottom of the case are each composed of two thicknesses of material, which thicknesses are disposed face to face, the case is strong against endwise stresses as well as lateral stresses, and not likely to be damaged in ordinary usage. The post-like structures of the four corners and middle of the case strengthen it vertically so that loaded cases may be stacked eight or more high without damage to the lower cases. The case of the present invention meets the shipping requirements of the railroads with a minimum of material, and in addition meets the shipper's requirement for uniform size compartments bounded by smooth parallel walls that are of uniform thickness throughout.

While I have chosen to show my invention by illustrating and describing a preferred embodiment of it, I have done so by way of example only, as there are many modifications and adaptations which can be made by one skilled in the art within the teachings of the invention.

Having thus complied with the statutes, and shown and described a preferred embodiment of the invention, what I consider new and desire to have protected by Letters Patent is pointed out in the appended claims.

What is claimed is:

1. A shipping case for fragile articles comprising integral bottom and side wall members, flanges at both ends of said members, a pair of liner members each having bottom and side wall sections, flanges on each end of each liner member, said liner members being disposed end to end and on said bottom member with the wide wall sections of the liners disposed against said side wall members, the flanges on said liners abutting together to form a vertical post alongside each side wall member and a horizontal post extending between the vertical posts and alongside said bottom member, the flanges on the ends of said liners with the corresponding flanges at the ends of said members forming corresponding vertical and horizontal posts at the ends of said case, generally U-shaped members having planar sections disposed against opposite faces of said posts and slotted connecting sections extending across the upper ends of the vertical ones of said posts, and means securing the planar sections of said case to said posts to close in the case and to divide the case into two equal compartments.

2. In a shipping case for fragile articles composed of double-face corrugated fiber board; a pair of compartments each bounded by smooth planar walls the opposite ones of which are parallel, each compartment having a bottom composed of two thicknesses of said material, side walls composed of two thicknesses of the material each thickness of which is integral with the thickness of the bottom, an end wall composed of two thicknesses of material spaced apart a distance equal to two thicknesses of the material both of which thicknesses are fastened directly to both the bottom and side walls; a partition joining together and separating said compartments, which partition comprises two thicknesses of said material separated by a space equal to two thicknesses of the material both of which thicknesses are fastened directly to both

the bottom and side walls; a cover for the case composed of a single thickness of the material, and double thickness notched projections on said cover adapted to extend through slots contained in the upper edges of said end and partition members and to engage the ends of those slots to lock the cover to the case at both ends and in the middle.

3. A shipping case for fragile articles comprising an outer member forming the bottom and side walls of the case, flanges extending upwardly from each end of the bottom and inwardly from each end of the side wall portions of said member, a pair of liner members each having a bottom section and two side wall sections disposed end to end against the bottom and side wall sections respectively of said outer member, flanges on each end of each of said liner members projecting upwardly from the bottom section and inwardly from the side sections and each lying alongside a corresponding flange on another member, a pair of U-shaped end members each straddling the end flanges on the outer and liner members, means securing said end members to said flanges to hold the case together, a U-shaped partition member straddling the flanges on said liner members at the center of the case, means securing said partition member to the flanges it engages to divide the case into equal size compartments, there being slots formed in the closed ends of said end and partition members, a cover, and tongues on said cover adapted to project through said slots and lock the cover to the case at both ends and in the middle.

4. In a shipping case for fragile articles, composed of double face corrugated fiberboard, double bottom and side wall members integrally connected together to strengthen the case against endwise shocks; posts at the ends of the side wall members formed integral with the side walls; double thickness end wall members each thickness of which is fastened to said bottom and to said posts, the thicknesses of board in said end wall being spaced apart by said posts to cushion the case against endwise shock; posts at the middle of the case formed integral with the inner thicknesses of the side wall members, a partition extending between the side wall members to divide the case into compartments and composed of two thicknesses of board each of which engages said latter posts and is fastened thereto and to the bottom to brace the case against lateral expansion under endwise stress, said thicknesses of board in the partition being spaced apart by said latter posts to cushion the partition against endwise shock, said end and partition posts reinforcing the case vertically against crushing under stresses imposed by stacking the cases one upon another.
